(57) CLAIM

The ornamental design for a golf club head, as shown and described.

DESCRIPTION

The sole FIGURE is a right side elevational view of an ornamental design for a golf club head.

The dash-dash-dash lines illustrate portions of the golf club head that form no part of the claimed design. The dash-dot-dash lines are included for the purpose of illustrating boundary lines and form no part of the claimed design.

1 Claim, 1 Drawing Sheet
